FISHING BAIT

Ernest M. Kuehl, Birmingham, Mich.

Application October 10, 1957, Serial No. 48,055

Term of patent 14 years

(Cl. D31—4)

Fig. 1

Fig. 2

5-5

Fig. 3

Fig. 4

Fig. 5

Fig. 1 is a top plan view of a Fishing Bait showing my new design;

Fig. 2 is a side elevational view thereof;

Fig. 3 is a bottom plan view of Fig. 1;

Fig. 4 is a front elevational view of Fig. 1; and

Fig. 5 is a vertical sectional view taken substantially on line 5—5 of Fig. 2.

The broken line representation of a hook in Figs. 1 and 2 is for illustrative purposes only.

I claim:

The ornamental design for a fishing bait, as shown and described.
